CLAIM

An ornamental design for a polyhedral optical conduit, as shown and described.

DESCRIPTION

FIG. 1 is an illustration of an isometric view of a first embodiment of the invention;

FIG. 2 is an illustration of a left end view of the embodiment of the invention shown in FIG. 1;

FIG. 3 is an illustration of a right end view of the embodiment of the invention shown in FIG. 1;

FIG. 4 is an illustration of a top side view of the embodiment of the invention shown in FIG. 1;

FIG. 5 is an illustration of a bottom side view of the embodiment of the invention shown in FIG. 1;

FIG. 6 is an illustration of a left side view of the embodiment of the invention shown in FIG. 1;

FIG. 7 is an illustration of a right side view of the embodiment of the invention shown in FIG. 1;

FIG. 8 is an illustration of an isometric view of a second embodiment of the invention;

FIG. 9 is an illustration of a left end view of the embodiment of the invention shown in FIG. 8;

FIG. 10 is an illustration of a right end view of the embodiment of the invention shown in FIG. 8;

FIG. 11 is an illustration of a top side view of the embodiment of the invention shown in FIG. 8;

FIG. 12 is an illustration of a bottom side view of the embodiment of the invention shown in FIG. 8;

FIG. 13 is an illustration of a left side view of the embodiment of the invention shown in FIG. 8; and,

FIG. 14 is an illustration of a right side view of the embodiment of the invention shown in FIG. 8.

The broken lines in the drawings show portions of the article and form no part of the claimed design.
